United States Patent Office.

ELISHA BRIGGS, SR., OF FAYETTE, IOWA.

Letters Patent No. 66,456, dated July 9, 1867.

IMPROVEMENT IN WATER-WHEELS.

The Schedule referred to in these Letters Patent and making part of the same.

TO WHOM IT MAY CONCERN:

Be it known that I, ELISHA BRIGGS, Sr., of the town and county of Fayette, in the State of Iowa, have invented a new improvement in Current Water-Wheels; and I do declare that the following is an accurate description thereof, reference being had to the accompanying drawings, and the letters of reference marked thereon, being made a part of this specification:

The nature of my invention consists in using the floats A A A, &c., with the valves a a a, &c., attached in the manner shown to the endless apron B B, (which is of the common construction,) all attached to the raft or frame C C, &c., by the hitching-bars F F. By means of the raft C C, &c., I am enabled to float the endless apron B B, carrying with it the floats A A A, &c., which contain the valves a a a, &c. By placing the raft with its attachments in the stream of water, the current acts upon the valves a a a, &c., in the floats A A A, &c., which, running the same way with the current, are carried around with the endless apron B B, ready to enter the water again as at L. The floats moving in this manner, communicate motion to the pulleys E E, &c., connected with main driving-shaft by means of chains K K. D D are wings that may be set at any angle for the purpose of throwing an additional current of water into the floats A A A &c., and valves a a a, &c. H H are braces designed to prevent the pressure of the water from dislodging the floats A A A, &c., from their proper position in relation to the apron. M M are simply flanges to hold the apron B B in its place as it revolves. O O are braces extending from the ends of the shafts upon which are placed the pulleys E E, &c., to the frame to hold these shafts in their places. When I wish to communicate the power from the pulleys E E to the main driving-shaft, I throw the hitching-bars back to the rear ends of the slots I I by loosening the chains T T, which are attached to a winch placed and operated as hereinafter described. By this means I tighten the chains K K, and so communicate the power. When it is desirable to stop the motion of the main shaft, I throw the hitching-bars forward in the slots I I, by tightening the chains T T, which are attached to a winch placed and operated as hereinafter described, which loosens the chains and accomplishes the purpose. The hitching-bars F F are connected with the frame C C by the bolts N N, which play in the slots I I. At the points P P I attach chains S S that are carried to the main beam, which chains hold the whole apparatus to its place in the stream. At R R I attach other smaller chains T T, the other ends of which are fastened to a winch placed upon the main beam for the purpose of throwing the hitching-bars F F forward or back as may be necessary. By turning the winch backwards, I loosen the chains T T, which allows the current of water to carry the endless apron B B, with its attachments, down the stream, until the chains K K are tightened around the pulleys E E, when the desired motion is communicated. By turning the winch the other way, I tighten the chains T T, and draw up the endless chain B B, which loosens the chains K K. relieves the friction upon the pulleys E E, and stops the communication of motion.

What I claim as my invention, and desire to secure by Letters Patent, is—

The arrangement and combination of the floats A A A, &c., with the valves a a a, &c., upon the endless apron B B, carrying the pulleys E E and the chains K K with the braces H H, the wings D D, the hitching-bars F F, the bolts N N, and the slots I I, and the whole attached and floated upon the frame or raft C C, all substantially as and for the purposes described.

ELISHA BRIGGS, Sr.
